UNITED STATES PATENT OFFICE.

LEVI SCOFIELD, OF GRAND HAVEN, MICHIGAN, ASSIGNOR TO THE CHALLENGE CORN PLANTER COMPANY, OF SAME PLACE.

CORN-PLANTER.

SPECIFICATION forming part of Letters Patent No. 313,891, dated March 17, 1885.

Application filed November 11, 1884. (Model.)

To all whom it may concern:

Be it known that I, LEVI SCOFIELD, of Grand Haven, in the county of Ottawa and State of Michigan, have invented certain new 5 and useful Improvements in Corn-Planters; and I do hereby declare the following to be a full, clear, and exact description of the same, reference being had to the accompanying drawings, forming a part of this specification, 10 and to the figures and letters of reference marked thereon.

My present invention relates particularly to improvements in the seed-plate-actuating mechanism of corn-planters; and it has for its 15 object to so construct such mechanism as that its parts can be very cheaply manufactured and put together with but little fitting up, and so that when in operation the friction will be reduced to the minimum.

20 In the accompanying drawings, Figure 1 represents a top plan view of one of the seed-boxes of a corn-planter. Fig. 2 is a similar view of the same, with the hopper and the bottom plate removed to show clearly the construction and arrangement of the improved seed-plate-actuating mechanism. Fig. 3 is a 25 side elevation of the seed-box, showing a portion of the beam upon which it is mounted. The upper part of the hopper in this view is 30 broken away. Fig. 4 is a side view, and Fig. 5 a bottom view, of one of the actuating-pawl. Fig. 6 is a perspective view of the reciprocating 35 swinging frame through which motion is imparted to the pawls and upon which the latter are preferably mounted.

Similar letters of reference in the several figures indicate the same parts.

A represents the plate or casting which forms the base of the seed-box, and serves to 40 connect the latter rigidly to the beam A' of the planter. This casting has horizontal flanges a a, which rest upon and are bolted to the beam, also upper flanges, a² a², which serve to guide the actuating-pawls in their 45 movements, and angular flanges a³ a³, to which the hopper of the seed-box is secured. It is further provided with a horizontal bearing for the seed-plate C to rest upon, a central stud, a', which forms a pivot for said seed- 50 plate to rotate upon, and finally with a down-

wardly-projecting tube or seed-conductor, F. The seed-plate C is provided with the usual seed-apertures, f, and with the peripheral ratchet-teeth c c, with which the actuating-pawls D D co-operate. These pawls are preferably arranged at opposite corners of a reciprocating swinging frame, H, and are by preference pivoted to the bolts G, which serve to connect said swinging frame to the upper ends of bifurcated arms or links E E, that bestride the beam, and are pivoted in turn thereto by bolts e, as shown in Fig. 3. Each of the pawls D is allowed a free vertical and a slight lateral play upon its pivot. On the side next the seed-plate it is provided with a projection 65 or stop, d, for arresting the rotation of the seed-plate at the proper time, and between this stop and its outer end it is curved or beveled, as shown in Figs. 5 and 6, for the purpose of causing it to be raised with greater 70 facility by the back of the teeth on the seed-plate when the latter is rotated, as will be further explained.

In the operation of the machine the swinging frame H is caused to vibrate back and forth upon its bifurcated arms or links by means of an ordinary connecting-rod, operated either by means of the dropper or by a check-rowing attachment in the usual manner. When the frame swings in one direction, the forward 75 end of one of the pawls, working in the space between the seed-plate and the vertical flange a², pushes against the face of one of the ratchet-teeth on the seed-plate, and causes a partial rotation of the seed-plate, while at the same 80 time the opposite or retracting pawl is struck on its under curved or beveled surface by the back of one of the other teeth of the seed-plate, and is lifted up and held elevated till the tooth passes under, when it falls by gravity in front of the tooth in position to operate 85 upon it when the frame is swung back in the opposite direction. The teeth on the seed-plate are so arranged with relation to the actuating-pawls that just before the advancing 90 pawl (whichever it may be) that is in engagement with one of the teeth reaches the limit of its forward movement the end of the other pawl drops off of the tooth which has raised it, ready to immediately co-operate with said 95 100

tooth when the motion of the swinging frame is reversed, and, therefore, so long as the swinging frame continues to vibrate, the seed-plate is given a regular intermittent forward motion 5 of positive character, so as to cause one or more of its filled orifices or pockets to deposit their contents into the depending seed-discharge tube F. As each pawl reaches the limit of its forward movement the back of the 10 next succeeding tooth to that on which it has operated moves up against the projection or stop d on its side, and thus effectually prevents the "racing" of the seed-plate, or, in other words, renders it impossible for the momentum of the plate, due to its quick forward impulse, from carrying the seed orifices or 15 pockets past the discharge-port. By mounting the pawl-carrying frame upon the swinging arms or supports a freedom of motion is given 20 the working parts, and the friction is reduced to a minimum, being confined, principally, to the two cross-bolts e e, upon which the lower ends of the vibratory arms are pivoted. The bifurcation of the supporting-arms 25 and causing them to embrace the beam prevents any lateral displacement of the parts when in operation. So admirably, indeed, is this frame hung that its movement in either direction is only required to be initiated, for 30 as soon as the centers of the supporting-arms are past the weight of the parts thereon continues or completes the movement. It sometimes happens that the movement imparted to the swinging frame in either direction by the 35 dropper or check rope is only partial, and that, consequently, the end of the pawl which is next to advance is left behind instead of in front of its corresponding tooth, the latter remaining under its curved or beveled portion 40 and in front of its projection or stop d. It therefore becomes necessary to provide against a dead-lock that might be produced by the contact of the stop of the pawl with the end or point of the tooth upon the forward movement of the pawl, and this I do by beveling the forward and outer portion of the stop, as 45 shown in Fig. 4 at d', so that should the point of the tooth strike it it will be deflected to one side, and thus prevent a stoppage of the mechanism. 50

The form of swinging pawl-carrying frame is susceptible of an infinite number of modifications; but I prefer to employ a frame having the form and characteristics of the one 55 shown in the drawings, and particularly in Fig. 6. As will be seen by reference to the last-named figure, it is formed of a single casting with forks or bifurcations h h, for the reception of the pivoted ends of the pawls, and 60 with openings h², for the passage of the cross-bolts G, which serve to joint it to the supporting-arms E. It is also provided with a stud, h³, for the attachment of the operating connecting-bar, and with depending lugs h⁴ h⁴, which

form a notch, into which is designed to project the upper end of the tip-valve, which makes the second or lower drop in planters of this class. Its shoulders h⁵ h⁵ are adapted to co-operate with the cross-plate of the main casting A at opposite sides, and to serve as 65 stops to limit the movement of the frame in both directions. When constructed in this form, the frame, by reason of its openness, leaves no surface upon which dust, dirt, or any foreign substance can find a lodging-place 70 and interfere with the working of the mechanism; moreover, no fitting up of the casting is required, except the reaming out of the bolt-holes, and the same bolts which serve to connect the frame with its supports also serve 75 as the pivots for the pawls. 80

It is perfectly obvious that the parts might be pivoted to independent bearings located at any suitable point on the swinging frame, or that they might be mounted on the swinging 85 arms instead of on the frame; but, as before stated, the construction hereinabove particularly described is deemed preferable for the reasons given.

Having thus described my invention, what I 90 claim as new is—

1. In a corn-planter, the combination, with a rotatable toothed seed-plate, of actuating-pawls, a support for said pawls, and vertically-swinging arms on which said support is 95 mounted and vibrates, substantially as described.

2. In a corn-planter, the combination, with a rotatable toothed seed-plate, of oppositely-acting gravitating pawls, a support for said 100 pawls, and vertically-swinging arms, on which said support is mounted and vibrates, substantially as described.

3. In a corn-planter, the combination, with a rotatable toothed seed-plate, of a horizontally-vibrating frame mounted upon and connecting vertically-swinging arms, and oppositely-acting gravitating pawls carried by 105 said frame for co-operating with said toothed seed-plate, substantially as described.

4. In a corn-planter, the combination, with a rotatable toothed seed-plate, of the beam, vertically-swinging arms pivoted to said beam below the seed-plate, a frame mounted on said 110 swinging arms, and a pair of oppositely-acting gravitating pawls carried by said frame, substantially as described.

5. In the herein-described corn-planter, the combination of the vertically-swinging supports, the horizontally-vibrating frame, and the 115 gravitating actuating-pawls having the stops on their sides with the rotatable toothed seed-plate, substantially as described.

6. The combination, with the rotatable toothed seed-plate, of the vibrating gravitating pawls having stops which at one side are flat, for arresting the teeth after full movements 120 of the pawls, and at the other side are inclined

or beveled, as at d' , for the purpose of preventing the locking of the teeth when partial movements only of the pawls occur, substantially as described.

5 7. The combination, with the rotatable seed-plate, of the horizontally-vibrating frame, its vertical swinging supports, the gravitating pawls, and the cross-bolts, which serve both for

the pivots of the pawls and as the means for connecting the frame to the supports, substantially as described.

LEVI SCOFIELD.
